METHOD FOR PRODUCING FUEL
CARBURETIONHarold W. Smith and Donald D. Paxton,
Los Angeles, Calif.

Application June 16, 1944, Serial No. 540,614

4 Claims. (Cl. 123—119)

This invention relates to a method for producing fuel carburetion, and is a division of our co-pending application Serial No. 499,680, filed August 23, 1943.

In the operation of internal combustion engines, and particularly airplane engines for military purposes, it has been found that the consumption of liquid fuel during the period of starting an engine is excessively high, and that it causes an engine to operate inefficiently. This is particularly true when the engines are operated under low temperature climatic conditions, for in such cases there is difficulty in starting the engine and properly warming it up for combat flight. In fact, it is often necessary to supply auxiliary heaters to heat the engine and its associated parts for one or two hours before attempting to start the engine under its own power. In connection with these operations it has been found desirable to supplement or substitute the usual liquid fuel supply with fuel having the characteristics of propane and butane, which are gaseous at normal temperature, since this type of fuel will operate rapidly and efficiently in starting an engine and getting it under conditions of flight. However, it has been found that when fuels of this type are used their physical state is not constant, for under some circumstances the fuel will be in its liquid state and under other circumstances in its vapor state. It is therefore desirable to maintain the fuel in a constant state for carburetion and to insure that the fuel volume increases in a substantially direct ratio to the increase in airflow into the engine as induced by engine suction. It is the principal object of the present invention, therefore, to provide a method of carburetion especially adapted for supplying auxiliary carburetion to engines operating at idling speeds, and which method is characterized by automatically regulating the inflow of fuel to the fuel suction line of the engine in a manner to insure that upon initial operation of the engine adequate fuel supply will be provided for starting purposes, regardless of whether or not the fuel is in a complete gaseous state, is partly gasified, or delivered to the carburetor in a liquid state, and that as the idling speed accelerates the volume of fuel flowing to the engine intake line will increase in direct proportion to the suction.

The present invention contemplates the carburetion of fuel for an internal combustion engine, which method involves the step of automatically priming the engine with rich fuel at initial low engine speeds and thereafter inter-

rupting the priming action and introducing a normal flow of fuel to the engine when the engine has attained a normal operating speed.

The invention is illustrated by way of example in the accompanying drawings in which:

Figure 1 is a view indicating a schematic arrangement of the auxiliary carburetor with relation to an airplane engine of the radial type, and by which apparatus the present method may be practised.

Fig. 2 is a view showing a plotted graph to indicate the increase in air and fuel flow with relation to the increase in engine suction as attained by the present method.

Fig. 3 is a view in central vertical section through the auxiliary carburetor with which the present method is practised.

Referring more particularly to the drawings, 10 indicates an engine fitted with a supercharger 11. The supercharger 11 is formed with a suitable connection 12 leading to the usual air inlet 13. Connected to the member 12 at a point between the air inlet 13 and the supercharger 11 is a fuel supply pipe 14. This is attached to the carburetor unit 15 with which the present invention is concerned. The carburetor unit has a bowl 16 formed with a radial opening 17 in its side to receive the fuel supply pipe 14. At the center of the bowl 16 is a valve chamber 18. The valve chamber 18 is at right angles to the radial opening 17 and is formed with threaded openings 19 and 20 at its opposite ends. These openings are vertically aligned. The upper opening receives a threaded valve seat structure 21, and the lower opening receives a threaded valve seat structure 22. A valve element 23 is disposed within the chamber 18 and moves upwardly against the valve seat 21. As will be hereinafter explained it is normally in its closed position.

A valve element 24 is disposed within the chamber 18 and moves downwardly onto the valve seat 22. This valve is normally disposed in its opened position. It will be seen that chamber 18 communicates with the passageway 17, and that

outflow of fluid may pass through either of the valve seats 21 or 22 when their valves are opened. The passageway through valve seat 21 communicates with a diaphragm chamber 25 which is closed by a diaphragm 26. The diaphragm 26

is fixed to the stem 27 of the valve 23 at its center and is secured over the upper end of the bowl 16 by a ring 28. The ring 28 is formed with a central passageway of two different diameters, the smaller diameter agreeing with the diameter of the diaphragm chamber 25 and the larger di-

ameter agreeing with that of a pressure space 29, which is formed by a cover plate 30. The plate 30 engages the marginal edge of an upper diaphragm 31. The diaphragms 26 and 31 define an intermediate pressure space 32. Attention is directed to the fact, however, that the upper diaphragm 31 is of larger area than the lower diaphragm 26, and that thus a differential action will be obtained as hereinafter explained. A spacer 33 is disposed between the center of the two diaphragms and is formed with an upwardly projecting threaded portion 34 which extends into a threaded opening in a rod 35. The upper end of the rod 35 is threaded at 36 to receive a nut 37 and to hold a disc 38. Interposed between the disc 38 and the upper face of the plate 30 is a spring 39 which tends to hold the diaphragms 26 and 31 upwardly and to hold the valve 23 on its seat. A cylindrical housing 40 is formed integral with the plate 30 and circumscribes the spring 39. The rod 35 when extending through the plate 30 has a free fit with the walls of opening 41 so that atmospheric air pressure will act upon the upper face of the diaphragm 31.

As here shown, the carburetor bowl 16 is formed with a radially disposed outlet opening 42. This is threaded and receives the end of pipe 14' connected with the suction side of the supercharger 11. At the inner end of the radial passageway 42 is a duct 43 which communicates with the space 32 between the diaphragms 26 and 31. At the inner end of the passageway 42 there is also a duct 44 which communicates with the chamber 25 occurring beneath diaphragm 26.

The valve 24 is fitted with a stem 45 which extends downwardly through the valve seat structure 22 and is formed with a threaded portion 46 receiving a nut 47. This threaded portion extends through the center of a diaphragm 48. The margin of this diaphragm is held against the lower face of the bowl 16 by the upper face of a housing 49. The housing 49 is substantially cylindrical and is formed intermediate its ends with an inwardly extending annular partition flange 50 which receives a valve cylinder 51. The valve cylinder 51 extends downwardly below the flange 50. Its lower end is closed by a cylinder head 52. The valve cylinder is formed with a partition 53 intermediate its ends. The partition has a central opening 54 through it. The upper face of the partition wall 53 surrounding the opening 54 is formed with a valve seat 55 upon which a valve 56 may rest. Disposed between the valve 56 and the central rigid portion of the diaphragm 48 is a spring 59. This tends to separate the valve and the diaphragm and to urge the diaphragm upwardly to a position against stop fingers 60 while urging the valve down onto its seat. The valve 56 is formed with a stem 61 which extends downwardly through the opening 54 and terminates in an enlarged disc 62. The disc 62 has upwardly extending stop fingers 63 which limit the upward movement of the valve. Disposed beneath the disc 62 and between it and the cylinder head 52 is a bellows 64, here shown as of the "Sylphon" type. This bellows is sealed at its opposite ends and is partially filled with the same type of fuel which is to be passed through the carburetor, such for example as propane. When stating that the bellows is partially filled with this fuel it is to be understood that the bellows is partially filled with liquid propane, and that during functioning of the carburetor the propane may

change from liquid to gaseous state in varying degrees. The bellows 64 is subjected to external pressure produced by fuel passing through ducts 65 in the side wall of the cylinder 51 and communicating with a cylindrical bore 66 of the housing 49. The fuel entering the bore 66 is conducted from the induction line 14 through a duct 67 in the bowl 16 to a duct 68 in the housing 49.

The lower end of the housing 49 is formed with a flange 69 against which a head 70 is secured by cap screws 71. This head closes the lower end of the bore 66 and is formed with an upwardly projecting annular flange 72 against which a valve cup 73 normally rests. The cup has a lower disc-shaped portion 74 resting directly on the flange 72 and is formed with a central passageway 75 and a plurality of other passageways 76 which are arranged circumferentially around the central passageway and are separate therefrom. A cylindrical wall section 77 extends upwardly from the disc portion 74 and provides a seat for a spring 78 which is disposed between the cup 73 and the transverse partition wall 50 of the housing 49. This tends to urge the cup to its lowermost position as limited by the annular flange 72.

Formed centrally of the head 70 is a threaded bore 79 which receives a valve seat 80. This valve seat is formed with a central opening 81 through which a valve stem 82 extends. This stem carries a valve 83 at its upper end and a valve 84 at its lower end. The valves are spaced from each other so that when they move to their alternate positions the passageway 81 will be closed. A disc 85 is associated with the valve 83 so that when it moves upwardly to engage the portion 74 of the cup 73 the upward movement of the valve structure will be limited. A rod 86 extends upwardly from the disc and into a spring cup 87 carried by the cylinder head 52. A spring 88 is disposed within the cup and around the rod and rests against the upper face of the portion 85 of the valve. This spring tends to urge the valve 83 downwardly against the seat 80, and thus normally closes the passageway 81. The lower end of the valve stem 82 is connected to a diaphragm 89 which is disposed between the member 70 and a cover plate 90. The cover plate 90 is formed with a port 91 communicating with the atmosphere and delivering atmospheric air into space 92 which occurs between the cover plate 90 and the diaphragm 89. A space 93 occurs between the diaphragm 89 and the member 70. This space communicates with the suction side of the carburetor through a priming passageway 94. The suction pipe 14' also communicates with a space 95 through a duct 96. The space 95 is defined between the diaphragm 48 and the lower face 87 of the bowl 16. A relatively small duct 98 establishes communication between the priming passageway 96 and a space 99 which occurs between the diaphragm 48 and the partition wall 53 of the housing 49.

The ducts 44 and 96 are fitted at points intermediate their ends with restricted orifice plates 100 and 101, respectively. These, together with the restricted orifice 98, tend to insure that there will not be an undesirable pressure drop when engine suction increases, and that the fuel entering the suction pipe 14' will be maintained at a constant increase in volume with relation to the increase in engine suction.

In operation of the carburetor with which the present invention is concerned it is to be understood that it is connected through the suction

pipe 14' to the conduit 12 leading from the member 13 to the supercharger 11. Under these circumstances the fuel delivered from a source of supply through the induction pipe 14 has a definite pressure. For the purposes of the present explanation it will be assumed that the fuel is propane and that the operating pressure is fifteen pounds gauge. This pressure is constantly imposed upon the various fluid responsive elements of the carburetor. At this time the valve 24 is held open by the spring 59 so that the fuel may pass downwardly through the valve seat 20 and into the chamber 95. At the same time fuel passes downwardly through the ducts 67 and 68 into the chamber 66 and from thence through the ports 65 into the valve cylinder 51 where it acts against the bellows 64. It is to be understood that when the engine is started under normal temperatures the fuel will be in a gaseous state and will be drawn through the carburetor in this state. It is intended that the fuel shall be in a liquid state when the engine has reached its operating temperature. It will be evident that since the bellows 64 is partially filled with propane that the pressure exerted by the fuel within the bellows will vary in direct relation to the fluid surrounding it. This will be due to the change of the propane from its liquid state to a gaseous state, at which time an increased volume of fluid will prevail within the bellows 64 tending to move the valve stem 61 upwardly and to lift the valve 56 from its seat. It is to be pointed out that as soon as the prevailing temperature drops to a point where the propane condenses the valve 56 will close. This drop in temperature will be produced as the engine speed accelerates and will cause the fuel passing through the carburetor to change to liquid phase, and the fuel which is sealed within the bellows will also condense. This last action will of course relieve the pressure exerted by the bellows and tending to lift the valve 56 from its seat. This compensates for the conditions created within the carburetor as produced by variation in the physical state of the propane fuel. It will be evident that the pressure of the gaseous fuel passing inwardly through the supply pipe 14 to the chamber 18 within the bowl 16 will act against the diaphragm 48, and that pressure of fluid passing through valve port 54 will oppose the downward movement of the diaphragm 48 and will be equal to the pressure of the fluid passing through valve 20. Since the pressures are balanced on both sides of diaphragm 48 valve 24 will be held open by spring 59, allowing gaseous fuel to flow through passageway 96 at full inlet pressure, thereby compensating for the changes in the physical state of the fuel passing through the carburetor.

During the initial stage of starting the engine, as previously discussed, it is to be understood that atmospheric air pressure acting upon the diaphragm 89 through the duct 91 will tend to open the valve 83. However, the springs 78 and 86 will act to close this valve. As suction increases in the suction pipe 14' a negative pressure will be imposed upon the upper face of the diaphragm 89 through the duct 94, and this will tend to lift the diaphragm 89 and to move the valve 83 from its seat. Fuel from the intake pipe 14 will then bypass the entire carburetor structure through ducts 67 and 68 and thence through the valve opening 81 to the chamber 93, after which it will be drawn directly into the suction line through the passageway 94. This will supply an initially greater volume of fuel 75

to the engine when starting and might be considered as producing an automatic priming action. When, however, the suction increases the diaphragm 89 will be lifted further, lifting cup 73, so that the valve 84 will close against the valve seat element 80 and will prevent a further priming action.

While the foregoing priming action is taking place it will be understood that fuel will be drawn directly from the induction pipe 14 to the education pipe 14' through the passageway 17 to the chamber 18 in the bowl 16 and thence through the valve seat 20 to the space 95 above the diaphragm 48, after which it will be drawn through the duct 96 into the education or suction pipe 14'. The restricted orifice 101 acts to meter the fuel to maintain a substantially constant volume. As previously explained, it will be assumed that the pressure of the incoming fuel is fifteen pounds gauge. This fuel pressure will be imposed upon the diaphragm 48, but the pressure of spring 59 is less than fifteen pounds gauge so that the pressure in chamber 95 will be reduced to a value determined by spring 59 and the suction imposed on lower side of diaphragm 48 through duct 98, maintaining a relatively constant volume of fuel flowing through orifice 101, regardless of suction in pipe 14'. As the engine speed accelerates the suction in pipe 14' increases. This acts to close the valve 84 and impose a negative pressure within the space 32 occurring between the diaphragms 26 and 31. These diaphragms are maintained normally in their uppermost position by the expansion of spring 39, since the diaphragm 31 is subjected to atmospheric pressure. When the negative pressure within the space 32 overcomes the pressure of spring 39 the atmospheric pressure exerted upon the upper face of the diaphragm 31 will cause the diaphragms 26 and 31 to flex downwardly and will move the valve 23 to an open position with relation to its valve seat 21. When the valve 23 moves to its open position fuel from the induction pipe 14 will pass through the valve seat 21 into the space 25 beneath the diaphragm 26 and will then be drawn through the restricted orifice 100 and the duct 44 to the suction pipe 14'. It will be understood that when the valve 23 moves to its open position immediately a portion of the fuel pressure is imposed upon the under face of diaphragm 26 and will tend to move the diaphragm upwardly and close the valve 23. However, the pressure area of the upper diaphragm 31 is greater than that of the diaphragm 26 and will oppose the closing action of the valve, regulating the pressure in chamber 25 to a value determined by the suction in space 32. The spring 39 will act as an intermediate variable factor between the two diaphragms in addition to their pressure area differences and will insure that a suction is built up in the line 14'. The volume of fuel drawn to the engine through the carburetor 15 will be increased proportionately to the increase in suction, to maintain a relatively constant ratio of the fuel to the air passing into the engine. This action is more particularly indicated in the graph here disclosed as Fig. 2, where it will be seen that while the suction-airflow varies somewhat from an absolute progressive ratio, and that the suction-fuel-flow varies somewhat from an absolute progressive ratio that the mean factors indicated by these two curves demonstrate that in the present device the fuel quantity flow progresses in substantially direct proportion to the airflow. It will thus be seen that the method here dis-

closed provides a simple fuel control whereby a fuel, such as propane, may be delivered to carburetion apparatus for engine starting, and will produce a preliminary priming action while in liquid phase and will tend to be converted to vapor phase for normal engine operations.

While we have shown the preferred method of practising our invention, it is to be understood that various changes in the steps of the operation may be made by those skilled in the art without departing from the spirit of the invention as claimed.

Having thus described our invention, what we claim and desire to secure by Letters Patent is:

1. A method of fuel control for carburetion in combination with an internal combustion engine, which fuel is characterized as being gaseous at normal temperatures and liquid at subnormal temperatures, said method consisting in delivering said fuel under pressure to a control structure and withdrawing fuel therefrom under engine suction, establishing a path of fluid flow from the induction to the eduction sides of said control structure, interposing a control valve in said path of travel normally held open, establishing a fluid flow from the induction to the eduction sides of said control structure, interposing an entrapped quantity of the fluid at a point in said last named path of travel and associating said quantity of entrapped fluid with said valve, whereby as the temperature of entrapped fluid is reduced by the flowing fluid the valve will be moved toward a closed position.

2. A method of fuel control for carburetion in combination with an internal combustion engine, which fuel is characterized as being gaseous at normal temperatures and liquid at subnormal temperatures, said method consisting in delivering said fuel under pressure to a control structure and withdrawing fuel therefrom under engine suction, establishing a path of fluid flow from the induction to the eduction sides of said control structure, interposing a pressure regulating valve in said path of travel normally held open, providing a normal feed path of travel of fuel from the induction passageway to the eduction passageway, interposing an initially closed valve in

said path of travel, and providing means subject to increased suction action whereby the valve in the normal feed path of travel will open as the engine speed accelerates.

3. A method of fuel control for carburetion in combination with an internal combustion engine, which fuel is characterized as being gaseous at normal temperatures and liquid at subnormal temperatures, said method consisting in delivering said fuel under pressure to a control structure and withdrawing fuel therefrom under engine suction, establishing a path of fluid flow from the induction to the eduction sides of said control structure along which a priming feed of fuel takes place, interposing a pressure regulating valve in said path of travel, whereby a predetermined degree of suction on the eduction side of the control unit will tend to decrease the opening of the valve as the engine speed increases, establishing a normal feed path of travel for fuel from the induction to the eduction sides of the unit, interposing an initially closed valve therein and providing means responsive to suction on the eduction side of the unit tending to open the valve in the normal feed path of travel as the engine speed accelerates.

4. A method of controlling a fuel, which is characterized as being gaseous at normal temperatures and liquid at subnormal temperatures and which fuel is delivered to the induction equipment of an internal combustion engine from a source of said fluid under pressure and through a control device having a priming passageway fitted with a pressure regulating valve responsive to engine suction and a normal feed passageway initially closed and responsive to engine suction, which method consists in delivering fuel under pressure to said control device, subjecting the control device to engine suction, whereby the priming flow valve will tend to close as engine speed accelerates, and subjecting the feed valve to engine suction whereby the feed valve will gradually open as engine speed accelerates to increase the fuel supply volume to the engine in substantially direct proportion to increase in engine suction.
